UNITED STATES PATENT OFFICE.

CHARLES W. BROCKETT, OF BROOKLYN, NEW YORK, ASSIGNOR TO W. R. OSTRANDER & COMPANY, OF NEW YORK, N. Y., A CORPORATION OF NEW YORK.

ELECTRIC SWITCH.

1,251,178.

Specification of Letters Patent. Patented Dec. 25, 1917.

Application filed January 18, 1918. Serial No. 72,707.

To all whom it may concern:

Be it known that I, CHARLES W. BROCKETT, a citizen of the United States of America, residing at Brooklyn, New York, N. Y., have invented a new and useful Electric Switch, of which the following is a specification.

My invention relates particularly to key socket switches and the important objects 10 of the invention are to simplify the construction and operation, to reduce the cost of production and to increase the current carrying capacity.

In a switch constructed in accordance 15 with my invention, the insulating supporting base is made in two complementary parts, forming between them at one side of the base an open-sided switch chamber in which is mounted a contact device in the 20 form of a yoke having spring contact arms which are forced upwardly and downwardly into engagement with contacts carried by the two parts of the base. These spring arms are actuated by a cam mounted 25 on a spindle which is journaled between the two parts of the base.

A special feature is the provision of a 30 post carried by one of the members of the base and provided with a bearing for supporting the outer end portion of the spindle.

Another special feature is a clip or bracket for securing the contact yoke in place, which is gripped between the two parts of the base.

Other features and details of construction will appear as the specification proceeds, attention being directed to the accompanying drawing, illustrating a concrete and practical form of the invention.

40 In the drawing:—

Figure 1, is a view in side elevation of a socket switch embodying the invention.

Fig. 2, is a front view of the same, looking into the switch chamber, the bearing 45 post for the spindle having been removed in this view and the spindle showing in section.

Fig. 3, is a view showing the opposite side of the switch from that shown in Fig. 1.

Fig. 4, is a rear view of the switch, showing the side opposite that in which the open-side switch chamber is formed.

Fig. 5, is a top plan view of the upper member of the base and the parts carried thereby.

Fig. 6, is a bottom plan view of the same.

Fig. 7 is a similar view of this base member alone.

Fig. 7^a is a top plan view of the lower base member.

Fig. 8, is a sectional view taken substantially on the plane of the line 8, 8, of the Fig. 5.

Figs. 9, and 10 are detail views of the contact yoke and bearing post.

In the construction illustrated, the switch base is made up of two complementary parts 10 and 11 secured together by through screws 12 and 13. These screws extend through the flange 14 of the screw shell 70 contact 15 and so serve to secure the screw shell contact in place as well as to fasten the two parts of the base together. One of these screws is utilized also as a current carrying conductor, screw 12 engaging at 75 its upper end with the angled foot 16 of a circuit terminal 17 located in a recess 18 in the edge of the upper base member 10.

The foot 16 of this circuit terminal seats in a recess 20 in the top of the upper base 80 member and this seat is preferably cut down as indicated at 21 to receive the end of the terminal binding screw 22. This cutting down of the seat 20 enables the assemblage of the parts by simply dropping the circuit terminal straight down on top of the securing screw entered from below and avoids the necessity of unscrewing the binding screw 22 before assembling the parts.

The other circuit wire is connected with 90 a terminal 25 disposed in a recess 26 formed in the edge of the upper base member opposite the first terminal notch. This terminal may be secured in place by a screw 27 passed down through the top of the upper 95 base member into engagement with the angular and laterally extending foot portion 28. This angularly extending foot portion

28 forms one of the switch contacts, projecting for that purpose into the upper portion of a switch chamber 29 provided between the two parts of the base.

5 This switch chamber is formed in the illustration by providing the upper base member with a recess 30 in one edge portion thereof and the other base member with a complementary recess 31, the two 10 recesses forming when the parts are combined a switch chamber substantially closed at the top and bottom but open at the side of the base.

Opposed to the contact member 28 carried 15 by the upper base member is a contact member 33 carried by the lower base member, this lower contact being secured in place by a screw 34 passed upward through the base member and engaged at the lower side there- 20 of with a center lamp contact 35.

The two switch contacts described are bridged, in circuit closing condition, by a yoke shaped spring, embodying an upright base portion 38 carrying at its opposite ends 25 spring contact arms 39 and 40 extending laterally in the switch chamber into a position to engage with the upper and lower switch contacts respectively.

This spring contact yoke is secured in position without weakening it with perforations for fastening, by supporting it between the meeting faces of the two members of the base. In the specific form illustrated the yoke is positioned and supported by a 35 bracket 43 looped about the base portion of the yoke as indicated at 47 and seated in registering slots 44 formed in the meeting faces of the two base members. Endwise displacement of this supporting bracket is 40 prevented by turning the outer end of the bracket at an angle as indicated at 45, said anchoring portion seating in the recesses 46 in the outer face of the base. This forms a very secure inexpensive and easily assembled mounting for the spring yoke. The 45 loop 47 which embraces or partially embraces the base portion of the yoke is preferably made large enough to permit the full spring action on the yoke, as indicated in 50 Fig. 2.

Vertical displacement of the spring yoke is prevented, in the illustration, by notching the forward or outer edge of the base portion of the yoke substantially as indicated 55 at 48 and engaging the loop 47 of the bracket in this notch. The base portion of the spring yoke may be stiffened somewhat by ribbing it longitudinally substantially as indicated at 49.

60 The spring contact arms are forced into engagement with the respective switch contacts by a spreading device in the form of a cam 50 mounted on the spindle 51. This cam is preferably made of metal so as to

carry a portion of the load at the breaking 65 of the circuit and thus relieve the spring yoke to a certain extent. The cam is loosely engaged on the spindle but rotates therewith when the spindle has been turned far enough to engage the outstanding projecting lugs 52 70 therewith.

The switch operating spindle 51 is journaled at its inner end between the two members of the switch base and at its outer end is provided with a key or other suitable actuating device 52. The outer end portion of this spindle is preferably braced and supported by journaling it in a post 53 secured to the upper base member and projecting downwardly into the switch chamber. In 80 this way the spindle is firmly supported at both ends. The inner end portion of the spindle which is journaled in the side portion of the base opposite that in which the switch chamber is formed, may rotate in 85 bearing washers 54 clamped between the meeting faces of the base members. The switch operating member is in this construction mounted on the spindle between the bearings therefor, resulting in a better mechanical operation and the bracing of the spindle at both ends also prevents the spindle acting as a lever to force the two base members apart. The journal post for the outer end of the spindle is in the illustration 90 formed with radial extensions 55 from the bearing opening therein to receive the radially projecting keying lugs 52 on the spindle.

The spindle bearing post 53 may conveniently be stamped from sheet metal and a convenient method of securing it in place is to pass the shank of the same upward through an opening in the upper base member and clench over the upper end of the 105 same at the top of said base member substantially as indicated at 56 in Fig. 5.

It will be noticed that in my construction the parts are all thoroughly insulated and that the cam operated spring contacts provide a quick acting double-make and double break. Furthermore at the instant of breaking the circuit the metal cam is in parallel with the contact arms across the break. All 110 these facts contribute to give the switch a high current carrying capacity. In addition to this important advantage, the switch is relatively inexpensive and the members which go to make up the base can be readily produced by a simple die action. 115

What I claim is:

1. In a switch of the character described, the combination of a two-part insulating base comprising upper and lower complementary members of insulating material arranged in abutting relation to thereby form a solid wall of insulating material and having complementary recesses at one side form- 120 125

- ing an open switch chamber in the side of the base, switch mechanism in said chamber, a switch operating spindle rotatably held at one end between the meeting faces 5 of the abutting insulating members of the base and extending out through the open side of the switch chamber and a post secured to one of the insulating members of the base at a point in line with the open 10 switch chamber and provided with a bearing receiving and supporting the outer opposite end portion of the spindle.
2. In a switch of the character described, the combination of a two-part insulating base comprising upper and lower complementary members providing a switch chamber therebetween, a spindle journaled in said base and passing through the switch chamber, a cam on said spindle within the 15 switch chamber, a contact carried by the upper base member within the switch chamber, a contact carried by the lower base member within the switch chamber, a contact yoke supported between the meeting faces 20 of said base members provided with spring arms passing above and below the cam and adapted to be forced upwardly and downwardly into engagement with the contacts carried by the upper and lower base members 25 respectively, a screw shell contact having an end flange engaged with the end face of one of said base members, screws passed through said end flange and through the base members to thereby secure all of said 30 parts together, a circuit terminal engaged by one of said screws whereby said screw shell is connected in circuit, a circuit terminal connected to one of the switch contacts and a center lamp contact connected to the 35 other switch contact.
3. In a switch of the character described, the combination of a two-part insulating base comprising upper and lower complementary members providing a switch chamber therebetween, said upper member having 40 terminal recesses in opposite edge portions thereof, a spindle journaled in said base and passing through the switch chamber, a cam on said spindle within the switch 45 chamber, a contact carried by the upper base member within the switch chamber, a contact carried by the lower base member within the switch chamber, a contact yoke supported between the meeting faces of said 50 base members provided with spring arms passing above and below the cam and adapted to be forced upwardly and downwardly into engagement with the contacts carried by the upper and lower base members 55 respectively, a screw shell contact having an end flange engaged with the end face of the lower base member, screws passed upwardly through said end flange and through the base members to thereby secure all of said 60 parts together, a circuit terminal seated in one of the edge recesses in the upper member and engaged by one of said screws whereby said screw shell is connected in circuit, a circuit terminal disposed in the other edge recess in the upper member and connected to 65 the switch contact carried by the upper base member and a center lamp contact connected to the switch contact carried by the lower base member.
4. In a switch of the character described, 70 the combination of a two-part insulating base comprising upper and lower complementary members providing a switch chamber therebetween, said complementary members having registering slots in the meeting faces thereof at one side of said switch chamber, a bracket seated in said slots and gripped thereby between said two base members, a contact yoke having a base portion engaged by said bracket and spaced spring 75 contact arms at the opposite ends of said base portion, a spindle journaled between the two members of the base, a cam on said spindle engaged between the spring contact arms of the yoke and contacts carried by the 80 upper and lower members of the base disposed in position to be engaged by the 85 spring contact arms.
5. In a switch of the character described, 90 the combination of a two-part insulating base comprising upper and lower complementary members providing a switch chamber therebetween, contacts carried by said respective members at the top and bottom of said switch chamber, a contact yoke in 95 said switch chamber having an upright base portion disposed at one side of said switch chamber and spaced spring contact arms at the opposite ends of said supported base 100 portion extending in a position to be engaged with the upper and lower switch contacts, a bracket looped about the upright base portion of the contact yoke and gripped between the meeting faces of the two base members and an operating cam 105 disposed between the spring contact arms and arranged to force the same into engagement with the respective switch contacts 110 therefor.
6. In a switch of the character described, 115 the combination of a two-part insulating base comprising complementary members forming a switch chamber therebetween, opposed contacts carried by said members, a 120 contact yoke comprising a base portion carrying spring contact arms for engagement with the switch contacts, the base portion of said yoke having a notch in one edge thereof, and a support-bracket for said yoke gripped between the meeting faces of the 125 base members and provided with a portion looped about the base portion of the yoke and engaged in the notch in the edge thereof.

7. In a switch of the character described, an insulating base having a seat in the top thereof and a recess in the edge adjoining, a circuit terminal disposed in said recess and having an angled foot engaged in said seat, a securing screw passed up through the base into engagement with said angled foot, an inwardly projecting binding screw carried by the circuit terminal and said base being cut down from the seat in the top 10 thereof to a point below the position of said binding screw whereby said circuit terminal with the binding screw extended may be dropped down on top of the securing screw.

CHARLES W. BROCKETT.
